UNITED STATES PATENT OFFICE.

JOHN G. CARLINET, OF PHILADELPHIA, PENNSYLVANIA, ASSIGNOR OF
SEVEN-TENTHS TO WILLIAM O'NEILL, JAMES WOLSTENCROFT, AND
WILLIAM H. SOLEY, OF SAME PLACE.

PNEUMATIC TOOL.

SPECIFICATION forming part of Letters Patent No. 498,742, dated May 30, 1893.

Application filed November 30, 1892. Serial No. 453,622. (No model.)

To all whom it may concern:

Be it known that I, JOHN G. CARLINET, a citizen of the United States, and a resident of Philadelphia, Pennsylvania, have invented
5 certain Improvements in Pneumatic Tools, of which the following is a specification.

The object of my invention is to construct a pneumatic tool that will deliver double the number of blows usually struck by pneumatic
10 hammers, my invention being an improvement upon the tool described and claimed in the application for patent filed by me on the 20th day of April, 1892, Serial No. 429,912.

In the accompanying drawings:—Figure 1, is a longitudinal sectional view of my improved pneumatic tool. Fig. 2, is a transverse sectional view on the line 1—2, Fig. 1. Fig. 3, is a view of a detail of the bushing, Fig. 1; and Fig. 4, is a view illustrating a modification of my invention.

A is the casing of the tool.

A' is a cap secured to one end of the casing; the tool carrier A² is mounted in the opposite end. The casing A is contracted at a and a', forming two internal flanges. The head of the tool carrier A' rests against the flange at a', as clearly shown in Fig. 1.

B is an internal sleeve or bushing in which the plungers slide, and this sleeve is confined
30 between packing b resting against an internal flange at a, and a flanged ring B' against which bears the cap A'. Between the bushing B and the case A, is an annular passage or air space c, forming a communication be-
35 tween the air inlet pipe C and the space w in front of the plunger D. The flange b' of the sleeve B is cut away as shown in Fig. 3, to allow the passage of air from the tube C to the space c, and passages c' are cut through
40 the forward end of the sleeve, and form a communication between the space c and the space w.

The cap B' has a series of openings c² which form communications between the tube C, and
45 and the space w' back of the plunger E; thus air under pressure is admitted to both ends of the tool, so that the tendency of the plungers D and E is to move to a central position,

but when air is admitted to the central air space w² between the two plungers, they are 50 forced apart owing to the fact that the area of the plungers acted upon by the air in the space w² is greater than the area of the plungers acted upon by air in the spaces w or w'. Air is admitted to the space w² through 55 the passage e in the extension E² of the plunger E, the passage e' and the passage e², as clearly shown in Fig. 1, so that when the plunger E nears the center line x, the passage e will be opened to receive air under press- 60 ure, as it will have passed the edge of the ring B'; but the passage of air is controlled by a valve F sliding in the space e', and as this valve is loose within the plunger, it has a tendency to remain in the position of rest while the 65 plunger moves forward; consequently the valve F will cut off the admission of air to the space w² at the proper time. When the plunger is returned the same action takes place, and the air in the space w² is not allowed to 70 exhaust until the plunger nears the end of its stroke. It will be noticed that the interior of the cap A is an exhaust chamber, with which the passage e communicates when the plunger is in the position shown in Fig. 1, and this 75 exhaust chamber communicates with the atmosphere through an opening a².

I preferably form between the cap A' and the ring B', an annular passage C' for the air under pressure, so that air can be admitted 80 to the spaces w, w' at more than one point.

The plunger D has an extension d', which, when the plunger is in the position shown in Fig. 1, is in contact with the head of the tool carrier A², this plunger striking the tool car- 85 rier in its forward movement when the plungers are separated. This extension D' as well as the plunger, is tubular, and passing through the plunger and extension is the extension E' of the plunger E, which, when the plungers 90 are moved toward each other to the center line, strikes the head of the tool carrier A² delivering its blow.

I preferably enlarge the extension at g, and also enlarge the openings in the plunger D, 95 and mount within this opening a suitable

packing g' , the packing acting to prevent leakage in the forward portion of the tool in the same manner as the packing b .

It will be seen that two blows are struck by the tool at one complete movement of the plungers, and the shock of each blow is taken up by the plunger not then in action. Thus the person using the tool is not subjected to the shocks which are unavoidable in tools as ordinarily constructed; therefore I not only gain the advantages described and claimed in the above mentioned application, but the tool will deliver a greater number of blows using the same amount of air under pressure.

15 In Fig. 4, I have shown a hollow plunger E , and adapted to slide within said hollow plunger is a plunger D , and in this instance only two air spaces are used, one on each side of the plunger D , the hollow plunger E acting as a valve to open and close the communicating passages. Both ends of the casing communicate with the atmosphere, and the passages are so formed in the plunger E , that they will exhaust the air from either side of the plunger D when the plunger E is moved, as will be readily understood by referring to Fig. 4.

A buffer i is adapted to a passage i' in the rear end of the casing or cap. This passage communicates with the air pressure pipe C , so that the buffer i is at all times projected against the rear end of the plunger E , and acts as a cushion for said plunger.

I claim as my invention—

35 1. The combination in a pneumatic tool, the tool carrier, two striking plungers and valve formations whereby the motive fluid is caused to act reversely upon the plungers so as to effect the retraction of one of said plungers 40 simultaneously with the advancement of the other, substantially as specified.

2. The combination, in a pneumatic tool, of the casing, the two striking plungers therein, one situated back of the other, and adapted 45 to strike at the same point, alternately, air inlet and exhaust ports controlling a passage of air to the tool, said ports being so arranged,

that when one plunger is striking the other plunger is recovering, substantially as described.

3. The combination of the casing, the forward plunger D , the rear plunger E , said plunger E having an extension passing through the forward plunger, air spaces w , w' at the end of the casing, and a central air space w^2 , 55 passages communicating with said air space, the valve for governing the flow of air to the central passage w^2 , substantially as described.

4. The combination of the casing, the plungers D and E therein, air passages in said casing, an air passage in the plunger E , with a valve carried by said plunger, but adapted to independently slide and regulate the flow of air through the passage in the plunger E , substantially as described.

5. The combination of the casing, the bushing B therein forming an air passage, plungers D and E adapted to slide in said bushing, a passage c' at the forward end of the bushing, ring B' at the opposite end, passages 70 therein, with a passage in the plunger E , substantially as described.

6. The combination in a pneumatic tool, of the casing A , a bushing B therein, a packing b confined by said bushing, a flanged ring B' resting upon the bushing and confined by a cap A' , a plunger D adapted to the bushing and having a tubular extension D' thereon passing through the packing, a plunger E having an extension E' passing through the plunger D , a rear extension E^2 extending through the ring B' , passage in the plunger E and its rear extension E^2 , with a port e forming a communication alternately between the air space and exhaust space, with a valve adapted to 85 open or close the said ports, substantially as described.

In testimony whereof I have signed my name to this specification in the presence of two subscribing witnesses.

JOHN G. CARLINET.
